Munn & Co.

ATTORNEY,

UNITED STATES PATENT OFFICE.

JOHN G. S. SMITH, OF ROME, GEORGIA, ASSIGNOR OF ONE-HALF TO JAMES A. TIGNOR, OF SAME PLACE.

BOUQUET-HOLDER.

SPECIFICATION forming part of Letters Patent No. 394,889, dated December 18, 1888.

Application filed April 30, 1888. Serial No. 272,241. (No model.)

To all whom it may concern:

Be it known that I, JOHN G. S. SMITH, of Rome, in the county of Floyd and State of Georgia, have invented a new and Improved 5 Bouquet-Holder, of which the following is a full, clear, and exact description.

The object of the invention is to provide a new and improved device for conveniently supporting bouquets, badges, &c., and attaching the same to clothing, drapery, &c.

The invention consists of a small bottle supported on a shield adapted to be secured to clothing or drapery by means of pins held in the said shield.

15 The invention also consists of certain parts and details and combinations of the same, as will be fully described hereinafter, and then pointed out in the claims.

Reference is to be had to the accompanying 20 drawings, forming a part of this specification, in which similar letters of reference indicate corresponding parts in all the figures.

Figure 1 is a perspective view of the improvement. Fig. 2 is a rear elevation of the 25 same. Fig. 3 is a front elevation of the same. Fig. 4 is a front view of a modification of the same, and Fig. 5 is a front view of a modified form of the improvement.

The improvement consists of a small bottle, 30 A, having a neck, B, engaged by the curved arms C, formed on the rods C' and passing through slots D, formed in the upper end of a shield, E, against the front of which said bottle A rests. The rods C' extend downward 35 on the rear of the said shield E and pass through eyes E', secured to the said shield E, and then the rods C' are continued in the upwardly-extending rods C², passed to the front of the shield E and through the slots D to the 40 rear of the shield and formed into the pins C³, which extend sidewise against the inwardly-bent flanges F, formed on the upper end of the shield E.

On the lower end of the shield C and at the 45 rear is formed an eye, E², in which is secured a rod, G, having the upwardly-extending ends G' passing to the front of the shield E and provided with the forwardly-extending parts G², which continue in the downwardly-extending ends G³, held against the front part of the

small bottle A, and adapted to carry a badge, H, as is plainly shown in Fig. 1, the upper edge of the said badge being folded and then passed under the upper part of the extending ends G² of the rods G G' G², so that the same press 55 the badge against the bottle A, as shown.

The pins C³ of the rods C are adapted to slide longitudinally in the slots D by pressing the upwardly-extending rods C² inward toward each other and then releasing the pressure on the said rods C².

The bottle A is filled with water, and then the natural flowers to be carried are inserted in the bottle, so that the stems of the flowers pass into the water, and thus the flowers receive nourishment and are kept fresh for a certain length of time. When it is desirable to use a bouquet of artificial flowers, the stems of the said artificial flowers are also inserted in the bottle A, but the latter is partially 65 filled with perfumery of any desired description.

In the modification shown in Fig. 4 the shield E is entirely dispensed with and the neck of the bottle A is encircled by a band or 70 ring, I, secured to the middle part of a rod, J, provided with the upwardly-extending rods J', having pins J², extending in opposite directions and adapted to be secured to the dress or drapery on which the holder is to be 75 used. A badge may be placed between the lower part of the rods J', which press the badge firmly against the bottle A, and thus hold the badge in place. A heavy badge—such as rosettes—is passed over the pins J². 80 85

Instead of employing the devices above described for securing the bottle, I may employ a collar, K, fastened directly to a shield, as illustrated in Fig. 5.

It will be seen that the device can be easily 90 attached to clothing or drapery by taking hold of the holder and pressing the arms C³ or J' inward and holding the back of the shield E against the part of the clothing or drapery to which it is to be attached, after 95 which the pressure on the rods C² or J² is released, so that the pins C³ or J², respectively, pass outward and into the clothing or drapery, thereby securely fastening the holder to the respective part to which it is to be attached. 100

The shield E may be made of wire instead of sheet metal, if desired.

Having thus described my invention, what I claim as new, and desire to secure by Letters 5 Patent, is—

1. In a bouquet-holder, the combination, with a bottle, of a shield carrying the said bottle, pins secured on the said shield for fastening it to the clothing or drapery, and 10 rods secured to the said shield and extending to the said bottle for supporting a badge, substantially as shown and described.

2. In a bouquet-holder, the combination, with a bottle, of a shield having slots and 15 supporting the said bottle, pins secured to the said shield and passing through the said slots, and flanges formed on the said shield and

against which operate the portions of said pins opposite their pointed ends, substantially as shown and described.

3. As a new article of manufacture, the bouquet-holder consisting of a bottle, A, held by the curved arms C of rods C' passing through slots D of shield E downward through eyes E', the upwardly-extending rods C², passing 25 in front of said shield and through said slots to the rear, and pins C³, extending against the bent flanges F of said shield, substantially as herein specified and shown.

JOHN G. S. SMITH.
